UNITED STATES PATENT OFFICE.

EARL A. HECHT, OF MANSFIELD, OHIO.

DESIGN FOR A TIRE TREAD.

Application filed August 22, 1923. Serial No. 7,063. Term of patent 14 years.

To all whom it may concern:

Be it known that I, EARL A. HECHT, residing at Mansfield, in the county of Richland and State of Ohio, a citizen of the United States of America, have invented a new, original, and ornamental Design for a Tire Tread, of which the following is a specification, reference being had to the accompanying drawing, forming a part thereof.

Fig. 1, is an elevation of a section of the periphery of the tire.

Fig. 2, is a cross section of the tire on the line *a—a* of Fig. 1.

I claim:

The ornamental design for a tire tread as shown.

EARL A. HECHT.
